TOY JACK-IN-THE-BOX

Robert Y. Allen and Melvin Shaw, Los Angeles, Calif.,
assignors to Hoover Products, Inc., Youngstown, Ohio,
a corporation of Ohio

Filed May 16, 1960, Ser. No. 60,600

Term of patent 14 years

(Cl. D34—15)

We claim:

The ornamental design for a toy jack-in-the-box, as shown.
